UNITED STATES PATENT OFFICE.

MALCOLM CURRY, OF HOLYOKE, MASSACHUSETTS, ASSIGNOR TO AMERICAN THREAD COMPANY, OF JERSEY CITY, NEW JERSEY, A CORPORATION OF NEW JERSEY.

MEANS FOR CONTROLLING HUMIDIFYING SYSTEMS.

1,282,763.

Specification of Letters Patent.

Patented Oct. 29, 1918.

Application filed December 5, 1917. Serial No. 205,703.

To all whom it may concern:

Be it known that I, **MALCOLM CURRY**, a citizen of the United States, residing at city of Holyoke, county of Hampden, State of Massachusetts, have invented a certain new and useful Improvement in Means for Controlling Humidifying Systems, of which the following is a full, clear, and exact description.

10 My invention relates to means for controlling humidifying systems and has for its object to produce a new and improved circuit controller which is simple in construction, effective in action and easily adjustable, also to produce a circuit controller which is inexpensive to construct and maintain.

15 The following is a description of an embodiment of my invention, reference being had to the accompanying drawings, in which:

20 Figure 1 shows diagrammatically a system having a circuit controller made in accordance with my invention;

25 Fig. 2 is an end view of the valve in the water supply pipe and the actuating mechanism therefor;

30 Fig. 3 is a detail, partially in section, showing one of the controlling contacts of my circuit controller; and

Fig. 4 shows a modified form of contact.

Referring more particularly to the drawings, 1-1 are humidifiers of ordinary form. They are supplied with water from a pipe 2, controlled by a balanced valve 3, water being supplied to said pipe through said valve from any convenient source of water pressure. The balanced valve 3 has an operating lever 4, which is connected at 5 to a chain 6, one leg of which contains a spring 7, so that the valve can be seated without damage to any parts, and is connected to a crank-arm 8 while the other end is connected to a crank-arm 9 of an actuating mechanism 10. The chain passes over a guide pulley 11, situated above the pipe 2, as shown more clearly in Fig. 2. The actuating mechanism 10 is of any suitable type. The form shown is intended to represent diagrammatically any one of several electrically-controlled spring driven step by step actuating devices now on the market for furnace regulators, and contains a motor for driving the arms 8 and 9, these arms being connected upon a common shaft rotating with the

disk 12, which is driven from the wheel 13 through an ordinary train of gearing. The disk 12 has in it two ratchet teeth 14-14, adapted to be engaged by a pivoted pawl 15 of magnetic material. The ratchet teeth 14-14 are diametrically opposite and when the pawl 15 is in engagement with either of them, the disk 12 is held from rotation. When, however, the pawl 15 is temporarily lifted by the electromagnet 15', the disk 12 85 revolves a half revolution until the other ratchet tooth is engaged and the disk is thereupon stopped. The disk 12 carries contacts 16-16' which alternately engage with two of three brushes forming terminals of 70 controlling electric circuits during successive rests of the disk; thus both the contacts 16-16' engage the brush connected with the circuit 17 while the contact 16, when the disk 12 is stationary in one position, engages 75 in addition the brush connected with the circuit 18. The contact 16', when the disk is stationary in the other position, with the pawl 15 in engagement with the ratchet tooth 14', makes engagement with the 80 brushes and the circuits 17 and 19.

The circuit 17 has its other terminal connected to the metallic frame 20 of a recording hygrometer forming part of my circuit controller and has within it a source of current, such as a dry battery 21. A small lamp 22 may be cut in and out of circuit by the switch 22', and being near the pointer of the hygrometer aids adjustment by its indication. The hygrometer is provided with the ordinary recording disk 23 and the marking pen pointer 24 pivotally mounted at 25 and also with suitable adjusting means 26. Slightly above the pivot 25 I rigidly connect a metallic cross-arm 27 to the member 24 and thus electrically connect it to the frame 20. This cross-arm is provided with loosely hanging contact-making devices 28 which are electrically connected to the member 24 and ground through the cross arm 27. These contact-making devices 28 pass through insulating caps 29 on conducting screws 30, having cavities in their upper ends containing mercury 31 and constituting circuit terminals whose contact surfaces 105 yield to pressure. These screws are carried by an insulating support 32 and are adjustable relatively thereto, being locked in position by lock nuts 33. This support 32 is pivoted at 34 to a suitable support, being 110

5 moved in one direction by a spring 35 and adjustable against such spring by an adjusting screw 36, so that the elevation of the screws 30 can be changed, one being raised while the other is lowered. The member 32 carries an indicating pointer 32', which moves in front of a scale upon the frame 20. The hygrometer is operated in a well known manner by horse hairs 37 connected fixedly 10 at their upper ends 38 to the upper portion of the instrument and at their lower ends to a sector 39, connected to the pointer 24. 40 is a counterbalance for holding the horse hairs 37 under tension.

15 In the operation of this device, the screws 30 are adjusted relatively to their support 32 in such position that when the pointer 24 is in a position to indicate the desired degree of moisture and the member 32 is substantially parallel to the bar 27, neither of 20 the contacts 28 will be in engagement with the mercury in the corresponding terminal. The separation, however, should be very slight so that a change of a small percentage in the moisture of the atmosphere will 25 result in a movement of the contacts 28 so that one of the contacts 28 will come in engagement with the mercury in the cup of its terminal and close the proper circuit 30 through the actuating device 10. When it is desired to adjust a circuit controller for another degree of humidity, the member 32 is adjusted by the screw 36 until the contacts 28 are out of electrical connection with 35 both contacts 30 when the pointer 24 is in a position to indicate the desired humidity. The controller therefor has in the adjustable terminals 30 means for adjustment for the amount of variation that can occur in 40 the humidity without actuating the circuit closer, and in the pivoted support 32 carrying the terminals 30 has means for adjusting the degree of humidity at which circuit closing will take place, subject to the variation permitted by the adjustment of the contacts 30.

With the parts as shown, the valve 3 is supposed to be closed. If the humidity becomes too low, the pointer 24 moves to the 50 left, closing the circuit through the left-hand contact 28 and cup 30 and establishes a connection through the circuit 18, which is completed by the contact 16 and conductor 17. This energizes the field magnet 15', which lifts the pawl 15, whereupon the clockwork begins to run and the lever arm 4 of the valve is elevated. After the arms 8 and 9 have turned through 180° , the disk 12 is stopped in such position that the contact 60 16' is in engagement with the brushes connected with the conductors 17 and 19. The valve 3 being thus opened, water is supplied to the humidifiers and the humidity of the air increases until when it has reached a 65 point slightly above that desired, the arm

24 of the indicator moves to the right, resulting in the closing of the circuits through the conductors 19 and 17 and the release of the actuator 10, which acts to restore the parts of the system to the positions shown in 70 the drawings with the valve 3 closed. When the humidity becomes too low, the first operation is again repeated and so on so long as the clockwork of the actuating device 10 is wound up, thus keeping the humidity of 75 the room substantially at any desired degree.

Where the humidifiers 10 are provided with electric fans 41, an electric circuit 42 is provided, having contacts 43 controlled by 80 contact 44 upon the switch arm 4, the contacts 43 being electrically connected when the valve 3 is open and disconnected so as to open the circuit when the valve 3 is closed. The circuit 42 can also be controlled 85 by a switch 45 so as to cut the fans 41 out of circuit irrespective of the condition of the valve 3. When the switch 45 is closed, the fan motor is started whenever the valve 3 is 90 opened.

Fig. 4 shows a modification in which, instead of having the loosely hanging contact 28 engaging mercury in a mercury cup, I provide a metallic chain 46, which is adapted to make and break contact with a rounded surface 47 of an adjustable terminal. The lowest link of this chain is electrically connected by a thin coiled wire 48 with the arm 27, the connections to the link and the arm being by solder. The sliding of the 100 chain over the convex surface of that terminal tends to keep it clean. In both forms at least one contact of each co-acting pair is a yielding contact permitting a pointer 24 to move after engagement is made so as 105 not to injure the hygrometer or interfere with its action.

As will be evident to those skilled in the art, my invention permits of various modifications without departing from the spirit 110 thereof or the scope of the appended claims.

What I claim is:—

1. In a circuit controller, a hygrometer having a member moving in accordance with changes in humidity, grounded contacts carried by said member, a pivoted support, additional contacts insulated from each other and carried by said support and co-acting with said first named contacts respectively so as to form two pairs of contacts, one contact of each pair yielding to pressure, and means for adjusting said pivoted support about its pivot.

2. In a circuit controller, a hygrometer having a member moving in accordance with 125 changes in humidity, grounded contacts carried by said member, a pivoted support, additional contacts insulated from each other and carried by said support and co-acting with said first named contacts respectively 130

so as to form two pairs of contacts, one contact of each pair yielding to pressure, means for adjusting said pivoted support about its pivot, and means for adjusting said additional contacts relatively to said pivoted support.

3. In a circuit controller, a hygrometer having a member moving in accordance with changes in humidity, grounded contacts carried by said member, a pivoted support, ad-

ditional contacts insulated from each other and carried by said support and co-acting with said first named contacts respectively so as to form two pairs of contacts, said additional contacts yielding to pressure exerted thereon by said first contacts, and means for adjusting said pivoted support about its pivot, and means for adjusting said additional contacts relatively to their support. 15

MALCOLM CURRY.
